UNITED STATES PATENT OFFICE.

HENRY J. ARMSTRONG, OF CHICAGO, ILLINOIS.

PORTRABLE HOUSE.

No. 892,571.

Specification of Letters Patent.

Patented July 7, 1908.

Application filed August 2, 1907. Serial No. 386,728.

To all whom it may concern:

Be it known that I, HENRY J. ARMSTRONG, a citizen of the United States, residing at Chicago, in the county of Cook and State of Illinois, have invented certain new and useful Improvements in Portable Houses, of which the following is a specification.

My invention relates to improvements in portable houses, of construction adapted to be readily set up for use or knocked down for storage or shipment, and it has for its object to provide a construction which is cheap, simple, easy to assemble or take apart, strong and durable, and weathertight.

Other and further objects of my invention will become apparent to those skilled in the art from the following description taken in conjunction with the accompanying drawing, wherein;

Figure 1 is a perspective view of a structure embodying my invention, with parts removed or broken away; Fig. 2 is a section on line 2—2 of Fig. 1; Fig. 3 is a section on line 3—3 of Fig. 1; Fig. 4 is a detailed section on line 4—4 of Fig. 1, and; Fig. 5 is a detail of the roofing.

Throughout the several views like numerals of reference refer always to like parts.

In the drawing 10—10 indicate uprights or posts, which may conveniently be six (6) in number in small houses, to provide four corner posts and a post in the middle of each side. In large constructions as many additional posts as are necessary may be provided.

At their bases the posts rest upon a foundation frame 11, of rectangular shape conforming with the contour of the house, the posts 10 being set square upon the foundation frame and secured thereto by small angle irons 12, each having one leg attached to the post and the other leg to the top of the foundation frame. At the top the posts are connected by a cap frame, consisting of side members 13 and a member 14, through which the ends of the posts 10 are mortised. Preferably the foundation frame 11 and the side members 13 of the cap frame project laterally beyond the edges of the posts 10; as best shown in Fig. 2.

Upon the cap frame are supported gable sections 15, each made for handling as a single piece, and providing inclined rafters, or roof beams, 16.

A suitable roof frame 17 may be centrally provided in alignment with the center posts 10 of the sides.

Connection is effected between the uprights or posts 10 and the roof rafters 16 of gables 15 and frame 17, by angle irons 18, arranged each with its vertical web flat against the posts or rafters, and its opposite web projecting at right angles outward from the post or rafter from the lower side of the vertical web, so as to form a seat. In the roof construction these angles extend only lengthwise of the building, but in the wall construction they extend along the sides of the building and along the end thereof in which there is no door, and which I will term the rear end. I prefer that some of the angle irons along the sides of the building be arranged so that their flat lower sides rest upon the top of foundation frame 11 and the cap frame side members 13, respectively, and extend flush with or project beyond the outer edges of such frame members. Thus the angle irons have firm bearing on their under sides and are as well secured at their rear edges to the uprights and the connected parts, and are accessible from the inside of the building.

The sides and rear end of the building are constructed of siding or covering sections 19—19, each section having on its rear face extending transversely thereof cleats 20—20, arranged so that when the siding sections are in place such cleats seat in the angle irons 18. The cleats are firmly held in the angle irons 18 by screw eyes 21, taking through suitable apertures 22 in the upright webs of the angle irons.

The roofing sections covering the roof rafters are constructed in panels in a generally similar manner, each panel preferably comprising roofing boards 24, covered over with sheet metal 25, of ribbed construction, having the ribs 26 underlaid with filling strips 27, the boards being so constructed that a rib 26 stands closely adjacent one edge of each board, while at its opposite edge a rib 26' of the metal hangs free over the edge of the board, so that in assembling the roof when the boards are brought side by side the overhanging rib 26' of one section overlies the edge rib 26 of the section next thereto, so forming a weathertight, broken joint. It will be understood that the roof sections 23—23 are provided with cleats and are se-

cured to the angle irons 18 in the same manner as are the siding sections.

The eaves of the roof may be closed by boards 28, carried by cleats 28' adapted to be hooked over the edges of the siding 19, as best shown in Fig. 2, and the roof is capped with an angular cap plate 29, having edge flanges 30 notched as at 31 to receive the ribs of the metallic roofing.

10 The front end of the building embodying the door may be built in any approved fashion, the sections adjacent the door being in my preferred construction permanently secured to the front corner posts, but any 15 other construction of the front may be used if preferred.

While I have herein described in some detail a specific embodiment of my invention, it will be apparent that changes may be made 20 therein without departure from its spirit and scope, and it will further be apparent that changes in size and proportions, bracings, and similar details may readily occur to those skilled in the art to adapt the construc-

tion to houses of larger or smaller size for 25 more or less severe use.

Having thus described my invention, what I claim and desire to secure by Letters Patent, of the United States, is:

In a portable house construction, a foundation frame, a cap frame, vertical posts connecting said frames and set inward at the sides from the edges of the frame, angle irons along the sides of the construction, having their horizontal webs resting on the base and cap frames, and their vertical webs rising from the inner side of the horizontal webs, siding, and cleats secured to the siding arranged to interfit in the angle irons, and means taking through the angle irons for securing the cleats in position.

In testimony whereof I hereunto set my hand in the presence of two witnesses.

HENRY J. ARMSTRONG.

In the presence of—

GEO. T. MAY, Jr.,

MARY F. ALLEN.
